UNITED STATES PATENT OFFICE

ADOLF STEINLE, OF JENA, GERMANY, ASSIGNOR TO THE FIRM N. V. NEDERLANDSCHE INSTRUMENTEN COMPAGNIE, OF THE HAGUE, NETHERLANDS

FIRING DIRECTOR

Application filed May 21, 1929, Serial No. 364,919, and in Germany May 26, 1928.

The invention concerns a firing director for shooting at moving targets, as e. g. aircraft or ships, and has for its object to provide for such firing director a device that in a simple manner allows to measure for an aim the setting forward angle that corresponds to the movement of the target, and the chart range of the point of impact, according to which two values a gun mounted at a certain distance from the firing director is to be laid.

In the drawings, Fig. 1 shows the positions of firing director, gun and target; Figs. 2 to 7 give an example of the invention. Fig. 2 is a diagram, where, for better understanding, some parts have been broken away. Figs. 3 to 6 are sections on the lines 3—3, 4—4, 5—5, and 6—6 in Fig. 2. Fig. 7 is a diagram on reduced scale. As Fig. 1 of the drawings shows, the example is based on the simplest case, i. e. it refers to targets that are in one horizontal plane with the firing director and the gun.

In Fig. 1 A is the site of the firing director, B that of the gun and C the instantaneous position of a target moving horizontally in the direction CD with a speed v_x . D is the locus of the target, which, after a time T, coincides with the point of impact of a projectile fired from the gun, whereby T is the time of flight of the projectile increased by a delay required for transmitting to the gun the aiming values and for making it ready to fire. The sighting values to be transmitted are the elevation of the gun barrel and the fuze setting that correspond to the chart range BD = E_2 of the point of impact, and the setting forward angle $\alpha + \beta$, wherein α is the angle between the chart base line AB = s and a line parallel to the line AC = E_1 which corresponds to the horizontal projection of the aiming line from the firing director to the target, and β is the angle enclosed by the said parallel line and the line BD. The value of the angle α being given, in the case of the new device only β and E_2 are to be measured.

According to the invention, the new device is provided with a line and a point, displaceably disposed relatively to each other in a plane and which are adjustable relatively to each other and of which the first corresponds

to the horizontal projection of the line from the observer to the target (hereinafter called the chart range), the second to the horizontal projection of the base line given by the different positions of the observer and the gun (hereinafter called the chart base line), and the third to the horizontal projection of the path of the target. The task is solved by displacing one of the marks relatively to the other in the said first direction by an amount corresponding to the chart range, in the said second direction by an amount corresponding to the chart base line and in the said third direction by an amount corresponding to the chart path of the target during the said time T, and by then suitably adjusting the line mark until it intersects the point mark, when the desired values can easily be read.

The adjustments are not necessarily to be made to suit the quadrangle ABDC (see Fig. 1), as, for instance, also the adjustment to a quadrangle ACEF, in which CE is parallel and equal to AB, EF parallel and equal to CD, and AF parallel and equal to BD, will allow to find the values of β and E_2 .

The different adjustments of the two marks relatively to each other can be effected by adjusting either the line mark alone, or the point mark alone, or both marks together.

The adjustments are conveniently regulated in such a way that the point mark is fixed on a mechanism similar to a double crank with arms of adjustable lengths, whereas the line mark, on one hand, is rotatably provided on an axis parallel to the turning axes of the two arms of the double crank, and, on the other hand, arranged in such a manner that it can be shifted in a direction corresponding to the shortest communication line between the turning axis of the line mark and the turning axis of the inside arm of the double crank.

The point mark is suitably represented by means of an illumination system and must appear either as light mark on dark ground or as dark mark on light ground, for which purpose a projection objective may be applied.

For measuring the chart range of the point of impact, it is convenient to provide an ap-

pliance with which, for changing the position in which one mark covers the turning axis of the line mark (i. e. the zero position) into that in which it coincides with the point 5 mark, the movement to be transmitted to one member is a measure for the distance of the point mark from the said turning axis. Such device enables this distance to be automatically transmitted to other parts of the 10 firing director for the purpose of ascertaining the fuze setting and the elevation of the barrel of the gun. Specially suitable for the purpose is an appliance that contains a disc which is rotatable on the turning axis of the 15 line mark and has an Archimedean spiral of which the pole is in the said turning axis and whose points represent actual chart range in such a way that, with one revolution at the utmost, the length of the radius 20 vector is altered by the difference between the longest and the shortest possible chart range of the target.

In the example given by Figures 2 to 7, a 25 is a base plate on which, along two guide rods a^0 , a slide e is movably arranged. This base plate carries a hollow column a^1 , in which a hollow shaft b turning on the axis $X-X$ is provided. This hollow shaft b carries a glass disc b^1 which is perpendicular to the axis 30 $X-X$ and whereof the upper surface b^2 is frosted, and provided with one coil of an Archimedean spiral b^3 whose pole is in the turning axis $X-X$. Each point of the spiral b^3 corresponds to a certain distance, viz. to the distance which is represented by the 35 length of the respective radius vector. The distance zero corresponds to the radius vector of the length zero, which belongs to a polar angle $\phi=0$ (taken from the tangent in 40 the pole of the spiral on the spiral itself), whereas the longest distance is represented by that radius vector that belongs to the polar angle $\phi=360^\circ$. The distances which are represented by the radii vectors between, are 45 proportional to the appertaining polar angles. In the hollow shaft b a shaft c , which also turns round the axis $X-X$, is rotatably provided. The said shaft c carries a transparent ruler c^1 which is next to the glass disc 50 b^1 and has on its lower surface c^2 , which faces the glass disc b^1 , a longitudinal line c^3 which intersects the turning axis $X-X$. By means of a knob c^4 the ruler c^1 can be turned round the axis $X-X$. For such purpose a toothed 55 wheel c^5 fast with the knob c^4 engages in the teeth c^6 of a gear c^7 which also is provided with a gear c^8 meshing with a gear c^9 on the shaft c . The angle β by which the ruler c^1 is turned out of its zero position, i. e. the position 60 in which its longitudinal line c^3 is parallel to the moving direction of the slide e , is indicated on a graduation c^{10} on the knob c^4 by a pointer c^2 of a bearing c^3 attached to the base plate a .

In order to have the glass disc b^1 coupled

to the ruler c^1 in such a manner that it takes part of the turning of same round the axis $X-X$, and also allows to be turned independently of the ruler so as to let it have that position which corresponds to the distance 73 to be adjusted, the following arrangement is made. On the shaft c^{11} , to which the gear c^7 is secured, there is fixed a gear c^{12} which is one of the two crown gears of a differential gear whose planet wheel d is on a shaft b^4 75 with bent end. The other crown gear is a gear b^5 which is connected rotatably to a shaft b^4 and rigidly to a gear b^6 . This gear b^6 engages in a gear b^7 secured to a shaft b^8 which can be turned by means of a knob b^9 . 80 The movements of the shaft b^4 which is bent on one end, are transmitted by means of two gears b^{10} and b^{11} , a shaft b^{12} and two conical gears b^{13} and b^{14} to the hollow shaft b . The arrangement is such that a complete rotation of the knob b^9 corresponds to a complete rotation 85 of the glass disc b^1 , relatively to the ruler c^1 . Such mutual adjustments of the glass disc b^1 and the ruler c^1 further can be made in such a way that, when a pointer a^2 of a bearing a^3 fixed to the base plate a points at the range zero of a scale b^{15} on the knob b^9 , which scale b^{15} is made to correspond to the actual chart ranges, the tangent on the spiral b^3 at the pole 90 coincides with the longitudinal line c^3 of the ruler. 95

In the drawings (see Fig. 7) the ruler c^1 is turned out of its zero position by an angle $\beta=30^\circ$. The intersection line of the spiral b^3 with the longitudinal line c^3 corresponds to a distance belonging to the polar angle $\phi=300^\circ$, i. e. a distance which amounts to $5/6$ of the longest possible distance that can be adjusted.

The aforesaid slide e carries a slide way f (Fig. 4) which, can be turned round an axis $Y-Y$ relatively to the slide e . This axis $Y-Y$ and the turning axis $X-X$ of the ruler c^1 are in a plane which is parallel to the moving direction of the slide e . Along the slide way f there is movably arranged a slide g carrying a slide way h which can be turned relatively to the slide g round the axis $Z-Z$. The turning axes $Z-Z$ and $Y-Y$ are in a plane which is parallel to the moving direction of the slide g . Along the slide way h a slide i is movably arranged. This slide carries a projection system containing an incandescent lamp k^1 , a punctiform diaphragm aperture k^2 and a projection objective k^3 whose axis $U-U$ contains the diaphragm aperture k^2 and is parallel to the turning axis $Z-Z$. Here the arrangement is made in such a manner that the axes $Z-Z$ and $U-U$ determine a plan which is parallel to the moving direction of the slide i , and that of the diaphragm aperture k^2 a sharp image of the form of a punctiform light mark M is projected on the frosted surface b^2 , which is provided with the spiral b^3 . 120 125 130

- and belongs to the glass plate b^1 , in such a way that the said punctiform light mark is on the axis U—U of the objective k^3 . The distance of the axis Y—Y from the axis X—X is indicated on the scale a^6 of the one guide rod a^6 by means of a pointer e^1 . The distance of the axes Y—Y and Z—Z from each other, is indicated on a scale f^1 of the slide way f by the edge g^1 of the slide g .
- 5 The distance of the axes U—U and Z—Z from each other, is indicated on a scale h^1 of the slide way h by the edge i^1 of the slide i . All three scales, a^6 , f^1 and h^1 , are to be imagined as numbered according to chart 10 ranges or distances. The angle by which the slide way f has been turned relatively to the slide way a^6 , is indicated by a pointer f^2 of the slide way f on a scale e^2 of the slide e , and the angle by which the slide way h has been turned relatively to the slide way f , by a pointer h^2 of the slide way h on a graduation g^2 of the slide g .
- 15 The operation of the device is as follows: The slides e , g and i are to be adjusted in such a way that the pointer e^1 indicates on the scale a^6 the chart range E^1 of the target C (compare also Fig. 1) from the firing director A, that, further, the edge g^1 of the slide g indicates on the scale f^1 the length of the chart 20 base line $CE=s$, which length is given by the different sites of firing director and gun, and that, finally, the edge i^1 of the slide i indicates on the scale h^1 the chart path $EF=v_g T$ of the target during the time of flight the 25 projectile requires till the impact takes place, increased by a certain time of delay. Here, on one hand, by turning it round the axis Y—Y, the slide way f must be adjusted in such a way that the pointer f^2 indicates on the 30 scale e^2 the angle α which is enclosed by the said chart base line and the horizontal projection of the aiming line from firing director to target aim, and, on the other hand, by turning it round the axis Z—Z, the slide way 35 h must be adjusted in such a way that the pointer h^2 indicates on the graduation g^2 an angle $\alpha-\gamma$, whereof γ is the angle between the chart path of the target and the said horizontal projection of the aiming line. By 40 turning the knob c^4 , the ruler c^1 must be adjusted in such a way that its horizontal line c^3 contains the punctiform light mark M which is projected on the glass disc b^1 by the projection device k^1 , k^2 , k^3 , and, by turning 45 the knob b^9 , the glass disc b^1 is given such a position that the spiral b^3 also contains the said light mark. Then the pointer a^2 will show on the graduation c^{10} the required angle β and the pointer a^4 on the scale b^{15} the required chart range E_2 of the point of impact. For further evaluation these two values are transmitted to other parts of the firing director (which are not shown on the drawings) by the shafts c^{11} and b^8 respectively.
- 50 The chart range E_1 of the target C from the firing director A, the said path $v_g T$ of the target, and the angle α , are submitted to continuous alterations, and, as a consequence thereof, the respective parts require to be continuously adjusted. By constructive measures, which are independent of the new device covered by the invention, it easily can be attained that the readjustments of the said parts as well as of those parts that require to be adjusted occasionally only (which latter are not shown in the drawings) are automatically transmitted by suitable couplings to the firing director and the gun.
- 55 I claim:
1. A firing director for shooting at moving targets, comprising a base plate, a ruler disposed over the base plate and being rotatable round an axis normal to said plate, the said ruler being provided with a longitudinal line which intersects this axis, means for 60 turning the ruler, an indicating device for indicating the position of the ruler relative to the base plate, a slide, a slide way disposed on this slide and being rotatable around a second axis which is parallel to the said first axis, a second indicating device for indicating the position of the slide way relative to the slide, the slide being disposed on the base plate for displacement in a direction parallel to the plane determined by the said two 65 axes and being perpendicular to these axes, a third indicating device for indicating the position of the slide relative to the base plate, a second slide, a second slide way disposed on this second slide and being rotatable round a third axis which is parallel to the two first-mentioned axes, a fourth indicating device for indicating the position of this second slide way relative to the said second slide, the said second slide being disposed on the 70 said first slide way and being displaceable in a direction which is parallel to the plane determined by the said third and second axes and being perpendicular to these axes, a fifth indicating device for indicating the position of this second slide relative to the said first slide way, a third slide carrying a point mark, this third slide being disposed on the 75 said second slide way for displacement in a direction which is parallel to the plane given by the point mark and the said third axis and being perpendicular to this third axis, and a sixth indicating device for indicating the position of this third slide relative to the said second slide way.
- 80 85 90 95 100 105 110 115 120 125 130
2. A firing director for shooting at moving targets, comprising a base plate, a frosted glass disc pivotally attached to the base plate, a ruler disposed on the base plate over and adjacent the disc and being rotatable around an axis, the said ruler being provided with a longitudinal line which intersects this axis, means for turning the ruler, an indicating device for indicating the position of the ruler relative to the base plate, a slide, a slide way

- disposed on this slide and being rotatable round a second axis which is parallel to the said first axis, a second indicating device for indicating the position of the slide way relative to the slide, the slide being disposed on the base plate for displacement in a direction parallel to the plane determined by the said two axes and being perpendicular to these axes, a third indicating device for indicating the position of the slide relative to the base plate, a second slide, a second slide way disposed on this second slide and being rotatable round a third axis which is parallel to the two first-mentioned axes, a fourth indicating device for indicating the position of this second slide way relative to the said second slide, the said second slide being disposed on the said first slide way and being displaceable in a direction which is parallel to the plane determined by the said third and second axes and being perpendicular to these axes, a sixth indicating device for indicating the position of this second slide relative to the said first slide way, a third slide carrying a point mark and a device for projecting this mark on the said glass disc, this third slide being disposed on the said second slide way for displacement in a direction which is parallel to the plane determined by the point mark and the said third axis and being perpendicular to this third axis, and a seventh indicating device for indicating the position of this third slide relative to the said second slide way.
3. A firing director for shooting at moving targets, comprising a base plate, a frosted glass disc disposed on the base plate for rotation round an axis, this glass disc being provided with an Archimedean spiral whose pole lies in the said axis, means for turning the glass disc, an indicating device for indicating the position of the glass disc relative to the base plate, a ruler disposed on the base plate over and adjacent the disc and being rotatable round the turning axis of the glass disc, the said ruler being provided with a longitudinal line which intersects this axis, means for turning the ruler, a second indicating device for indicating the position of the ruler relative to the base plate, a slide, a slide way disposed on this slide and being rotatable round a second axis which is parallel to the said first axis, a third indicating device for indicating the position of the slide way relative to the slide, the slide being disposed on the base plate for displacement in a direction parallel to the plane determined by the said two axes and being perpendicular to these axes, a fourth indicating device for indicating the position of the slide relative to the base plate, a second slide, a second slide way disposed on this second slide and being rotatable round a third axis which is parallel to the two first-mentioned axes, a fifth indicating device for indicating the position of this second slide way relative to the said
